UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,334,447.

Specification of Letters Patent. Patented Mar. 23, 1920.

Application filed September 14, 1917. Serial No. 191,368.

To all whom it may concern:

Be it known that I, CHARLES L. GOODRUM, a citizen of the United States, residing at New York, in the county of New York and State of New York, have invented certain new and useful Improvements in Telephone-Exchange Systems, of which the following is a full, clear, concise, and exact description.

- 10 This invention relates to telephone exchange systems employing machine switching, and is particularly adapted for use in a large system where a connection may lead over a relatively great number of what are known as selector or trunk-hunting switches. It frequently happens that after the calling subscriber has, by means of his finger wheel, partially built up a connection including a relatively large number of these selectors, 15 one is encountered having all the trunks in the desired group busy. Heretofore, in such event, the calling subscriber received a busy signal and had to replace his receiver, whereupon the set switches were all automatically restored to their normal positions. 20 On the subscriber's second attempt to set up such connection, a trunk in the group referred to may be idle, but all of those in the desired group of a preceding selector may be busy, so that he will be unable to build up the connection to such idle trunk.

This condition is particularly aggravating when a connection is built up as far as a connector switch leading to a private branch exchange. If, temporarily, no trunks to the P. B. X. are available and the calling subscriber is compelled to hang up and thereby restore all the switches, which condition is actually of frequent recurrence, 30 then the service is condemned as poor and the operating company suffers in consequence.

The object of the present invention is the provision of means which will make it unnecessary to release a connection when all the trunks of the desired group are busy. In the present embodiment of the invention, when a selector or trunk hunting connector finds that the entire group of trunks desired 40 is busy, it will wait in operative relation to such group, at the same time transmitting a busy signal to the calling party, thus informing him of the busy condition of such

group, and at the instant one of the trunks of the group becomes idle, will seize it, disconnecting the busy tone from the calling subscriber's line, whereupon the subscriber may transmit the next digit to set the selector in which the trunk so seized terminates or is put in instant communication with the operator of the P. B. X., if the P. B. X. is so arranged, or the subscriber may transmit the last digit to set the selective switch of the P. B. X. on the particular branch line desired.

The drawings consisting of two figures, Figure 2 being placed to the right of Fig. 1, illustrate a complete connection between a calling substation and a private branch exchange. Fig. 1 shows a calling substation and a trunk hunting selector switch embodying the features of the present invention. Fig. 2 shows a trunk hunting connector switch embodying the features of the present invention and a set of trunks leading to a private branch exchange and thence to a station within such exchange.

The calling substation A is adapted upon the removal of the receiver thereat, to be associated with a first selector indicated by the brushes b^2 , b^3 and terminals t^2 , t^3 , by means of a finder, whose brushes b , b^1 and terminals t , t^1 are shown. Brushes b^4 , b^5 and terminals t^4 , t^5 indicate another selector farther on in the train, the omitted selectors being indicated by the dotted conductors c^2 , c^3 .

The invention will be more readily understood by a detailed description of the operation. With reference to Fig. 1, when the subscriber at substation A removes his receiver from the hook, a line finder whose brushes b and b^1 only are shown, is automatically set in motion, seeking the terminals t , t^1 of substation A. The calling party then operates his sender 100 to set the train of selectors preceding the one shown in detail.

When the conductors c , c^1 of the calling substation A are extended to the selector 100 shown, the stepping relay 101 of said selector is energized over the following circuit: free pole of battery, left winding of relay 101, selector side-switch arm 1 and its first contact, terminal t^4 , brush b^4 , conductor c^2 , terminal t^2 , brush b^2 , brush b , terminal t .

2

5 terminal t , line conductor c^1 , through the telephonic apparatus at substation A, line conductor c , terminal t^1 , brushes b^1, b^2 , terminal t^2 , conductor c^2 , brush b^3 , terminal t^3 , selector side-switch arm 2 and its first contact, right winding of relay 101, to ground. Relay 101 in attracting its armature energizes a slow relay 102. This relay at its left armature prepares a circuit for primary stepping magnet 113, and at its right armature energizes a relay 120 which interposes a break in the circuit of release magnet 107.

10 The subscriber now operates his sender 100, transmitting the digit of the called 15 number with which the particular selector shown is concerned. The slow relay 102 holds its armatures attracted while the sender is interrupting the line circuit. The relay 101, however, is deenergized once for 20 each interruption of the line circuit by the sender, and at its armature and back contact transmits impulses over the armature and front contact of relay 102 and the secondary off-normal contact 103, to the primary stepping magnet 113 of the selector.

25 In parallel with primary magnet 113, a slow relay 114 is energized while the sender 100 is operating. This relay, in attracting its armature, energizes the side-switch escape magnet 115. When the sender 100 restores and maintains the line circuit closed, relay 101 remains energized, and relay 114 after an interval releases its armature, which deenergizes the escape magnet 115, 30 releasing the side switch into position 2.

35 During the primary movement of the brushes of this selector switch, a brush 108 has moved with the shaft 109 and been directively placed on the terminal 123 through 40 the action of the primary magnet 113. We will assume in this case that ground is placed on the terminal 123 due to the busy condition of all trunks in the group. This ground is extended through the armatures 45 and contacts of relay a^2, a^3 and a , in a manner to be hereinafter described and projected thence over the brush 108, the second position contact and arm 5, the relay 117 to free pole of battery. Relay 117 opens the circuit 50 for the secondary stepping magnet to be hereinafter described, and prevents the escape magnet 115 from energizing. At its right armature and contact relay 117 connects a source of busy tone 118 to the right winding of line relay 101, whence through 55 the inductive action of the two windings of this relay, the busy tone is transmitted to the calling subscriber's substation.

60 Upon hearing this busy tone, the subscriber at substation A realizes that all of the trunks leading from the selector switch, which he has just actuated, are busy and that the sending of further impulses at the present time would be useless. He therefore 65 waits for the busy tone to be removed which

will indicate that a trunk has become idle and that he may proceed with the connection.

Suppose a trunk whose terminals are here marked 110, 111 and 112, becomes idle, the relay a will become deenergized in a manner to be hereinafter described and the ground upon terminal 123 will be removed, as a consequence of which relay 117 will become deenergized, the busy tone will be removed 75 from the subscriber's line and the action of the switch will be taken up again at the point where the side switch wipers through the deenergization of the escape magnet 115 were moved into their second positions. 80

Since one of the trunks in the group upon which the selector has been set is now idle, side switch arm 4 in position 2 closes the following circuit: free pole of battery, secondary stepping magnet 116, its armature 85 and back contact, left armature and back contact of relay 117, right winding of magnet 115, arm 4 and its second contact to ground. The resistance of magnets 116 and 115 are so adjusted that magnet 115 energizes before magnet 116, and the magnet 116 is arranged not to open the circuit traced until near the end of its stroke, at which moment test brush 106 will have reached the test multiple 112 of the first trunk of the 90 group. Busy trunks are those whose test terminals are grounded. Consequently as long as busy trunks are encountered, the escape magnet 115 will be maintained energized over its left winding and arm 3 and 95 its second contact. When an idle trunk is reached, indicated by the absence of ground on its test terminal 112, escape magnet 115 deenergizes, releasing the side switch to position 3. Arm 4 in leaving position 2, opens 100 the stepping circuit of magnet 116, thus stopping the selector upon the terminals 110, 111 and 112 of the seized trunk. Arms 1 and 2 of the side switch in moving into position 3, extend the calking line through to 105 the selector brushes 104 and 105 and thence to the windings of calling supervisory relay 200, which is energized over a circuit including the calling subscriber's substation in the well known manner. In moving off 110 their second contacts these arms deenergize relay 101 which opens the circuit of relay 102. This relay however, is slow to release and before it retracts its armatures, test wire 121 is grounded at the connector 115 switch through the energization of the first slow relay 201, responsive to the energization of relay 200. This ground is transmitted over arm 3 and its third contact to relay 120, which maintains open the circuit 120 of release magnet 107 to prevent premature release of the selector. This hold-over arrangement is well known in the art and therefore is not shown in detail.

The ground on conductor 121 also causes 130

the seized trunk to test busy to other testing selectors and operates a relay α which by attracting its armature, closes one break between the commutator segment 123 and 5 ground as before described.

The energization of relay 200, as mentioned, causes in turn the energization of the first slow relay 201, which prepares a circuit for the transmission of impulses 10 in response to the operation of the dial 100. Upon the interruption of the busy tone, the seizure of the connector switch has taken place, as described and the subscriber at substation A proceeds to manipulate the sender 15 100 to send another series of impulses. At each break in the line circuit, the relay 200 retracts its armature thus transmitting an impulse from ground over the armature and back contact of relay 200, the inner right hand armature and front contact of relay 201, the winding of the second slow relay 202 to free pole of battery, thereby causing 20 the second slow relay to remain energized during the sending of this series of impulses. 25 Upon attracting its armatures, relay 202 closes a circuit from ground, armature and back contact of relay 203, front contact and inner right hand armature of relay 202, winding of escape magnet 204 to free pole 30 of battery. After the armature of relay 200 has been retracted once, the relay 202 has been energized and in turn the relay 204 has also been energized. Upon each attracted 35 movement of the armature of relay 200, an impulse will be transmitted from ground, the armature and front contact of relay 200, the left hand armature of relay 202, the arm 205 and its first contact, winding of primary magnet 206 to free pole of battery, where- 40 upon the shaft carrying the brushes 207 to 210 inclusive, is rotated step by step until the proper group is selected.

Upon the cessation of this series of impulses, the second slow relay deenergizes after a short interval and by opening the circuit of escape magnet 204 at its right hand armature causes the deenergization of the relay 204 and the consequent movement of the side switch arms into their second positions. 50 The subscriber at substation A now manipulates his dial 100 to send the units series of impulses, thereby setting the brushes 207 to 210 inclusive on the first trunk of the group leading to the desired P. B. X. The action of the different relays and magnets during the sending of this series of impulses, is the same as that just described with the exception that the side switch arm 205 being in connection 55 with its second contact, the secondary magnet 211 is energized instead of the primary magnet 206. At the end of this series of impulses, the relay 202 is again deenergized and under ordinary conditions the escape 60 magnet 204 would in turn be deenergized 65

and move the side switch arms into the third position. However, we will assume all trunks in the group leading to the desired P. B. X. are busy, in other words, that relays α^3 , α^4 , and α^5 , are energized. The 70 ground is now projected through the armatures and contacts of relays α^3 , α^4 and α^5 to the terminal 212, thence over the brush 210, the side switch arm 213 and its second position contact, the right winding of relay 214 to free pole of battery. Relay 214 is energized and through its outer right hand armature places a ground on the winding of escape magnet 204 to hold it energized and thereby prevent the movement of 80 the side switch arms into their third position.

At this time a busy tone is transmitted from the source of busy tone 215 over the secondary off-normal contact 216, the second position contact of side switch arm 217, 85 the left hand winding of the called supervisory relay 218 to free pole of battery, and through the inductive action of the windings of this relay such busy tone is transmitted 90 to the calling substation A.

As before, the subscriber at this substation realizes that all trunks in the group which he has now selected are temporarily busy and he therefore waits until the busy 95 tone ceases. The cessation of the busy tone is brought about in the following manner: one of the trunks leading to the desired P. B. X. becomes idle, and say relay α^3 becomes deenergized, thereby opening the 100 circuit from ground through the winding of relay 214 to free pole of battery. The device 219 which consists essentially of a constantly rotating shaft, carrying a number of commutator segments, causes the relay 214 105 to be energized through its left hand winding until the shaft has rotated to a certain position. When this has occurred, the circuit from ground through the device 219, the left hand armature and contact and 110 left hand winding of relay 214 to free pole of battery, is opened for an instant and if the relay 214 is not energized through its right hand winding, it releases its armatures. The device 219 is used for the purpose of preventing more than one connector, 115 which may be set and waiting for connection to an idle trunk in the same group, from hunting at the same time, and is provided to prevent a possible double connection. 120 As indicated on the drawing by the black segments of the commutators, the instants at which the circuits traced through the left hand winding of relay 214 will be opened, are displaced in the different connector switches served by the device. 125

When relay 214 releases its armatures, a circuit is established from ground, first test terminal in the selected group providing the first trunk is busy, to the brush 209, 130

the side switch arm 221 and its second position contact, back contact and inner right hand armature of relay 214 and back contact and outer armature of relay 202, winding of relay 222 to free pole of battery. Relay 222 attracts its armatures and establishes a circuit from ground, the front contact and right hand armature of relay 222, the armature and contact of secondary stepping magnet 211, the winding of this magnet to free pole 211, the winding of this magnet to free pole of battery. Through the automatic operation of secondary stepping magnet 211, the brushes 207 to 210 are moved step by step over the terminals of the desired group until an idle trunk is encountered. Assume that the trunk connected to terminals 220, 223, and 224 is idle. Upon the encounter of brush 209 with terminal 220 or should terminal 220 be the first in the group, the same will hold true, the circuit traced through the arm 221 for the energization of relay 222 will be opened. Relay 222 will be deenergized in the one case or will not be energized at all in the other case. If relay 222 were energized, during its energization a circuit is closed from ground, its front contact and left hand armature, the winding of escape magnet 204 to free pole of battery, and at its deenergization this circuit is opened. If relay 222 is not energized at all, due to the fact that the brushes of the connector switch rest upon the terminals of the trunk which has become idle, then this circuit for the energization of escape magnet 204 is not closed, and upon the deenergization of relay 214, as before described, and the consequent opening of the circuit from ground at the front contact and outermost right hand armature of relay 214, the escape magnet 204 is deenergized. Upon retracting its armatures therefore, the escape magnet under any one of these conditions will move the side switch arms into third position, whereupon a ringing circuit is established.

Ground is connected through the armature and back contact of ringing relay 203, the third position contact of side switch arm 225, the winding of escape magnet 204 to free pole of battery. Ringing current is generated by the generator 226 and transmitted over the circuit including the winding of marginal ringing cut-off relay 203, front contact and right hand armature of escape magnet 204, third position contact and side switch arm 227, brush 208, terminal 223, thence over the selected trunk to the apparatus at the P. B. X. back to the terminal 224, the brush 207, the side switch arm 228 and its third position contact to ground. When in response to the apparatus controlled by the ringing current, the subscriber at the P. B. X. seizes this trunk in any well known manner, the current through the marginal ringing cut-off relay 203 which hereto-

fore was insufficient to energize this relay, is now increased to the point where said relay does become energized and upon attracting its armature, it opens the circuit of the escape magnet 204. Upon its deenergization, the escape magnet moves the side switch arms into their fourth positions and connects through the arms 227 and 228 the calling substation A to the operator at the P. B. X. who in response to the calling subscriber's request, will in the well known manner connect him to the called substation B.

Upon the cessation of a conversation, the subscriber at substation A replaces his receiver on the hook as a consequence of which relay 200 is deenergized and the first slow relay 201 is allowed to retract its armatures, whereupon a circuit is established from ground, the armature and back contact of relay 203, the back contact and left hand armature of relay 201, the primary off-normal contact 229, the winding of release relay 230 to free pole of battery. At the same time ground at the outer right hand armature of relay 201 is removed from the test conductor 121, whereupon the relay 120 becomes deenergized and sets up a circuit for the energization of release magnet 107. The release of these selector switches upon the energization of their release magnets, is well known in the art and will therefore not be described in the present instance.

What is claimed is:

1. In a telephone exchange system, the combination with telephone lines, an automatic selective switch having trunk terminals arranged in groups, a sender adapted to set said switch in operative relation to one of said groups and means for thereupon automatically causing said switch to test the trunks of said group, of means rendered operative if all trunks of the selected group are busy for preventing said testing operation from taking place, and means actuated when a trunk of the group becomes idle for causing said switch to test said trunks.

2. In a telephone exchange system, the combination with telephone lines, an automatic selective switch having trunk terminals arranged in groups, a sender adapted to set said switch in operative relation to one of said groups by a movement in a primary direction and means for thereupon automatically causing said switch to test the trunks of said group, of means actuated upon the termination of the primary movement of said switch if all trunks in said group are busy for preventing such testing operation from ensuing, and means actuated when a trunk of the group becomes idle for causing said switch to test said trunks.

3. In a telephone exchange system, the combination with telephone lines, an automatic selective switch having trunk terminals arranged in groups, a sender adapted

- to set said switch in operative relation to one of said groups, means for thereupon automatically driving said switch over said group, of a relay for each trunk operated 5 when such trunk is seized, a circuit closed when all the relays of a group are operated and including means for disabling said driving means, and means actuated when a trunk of the group becomes idle for opening said 10 circuit to render said driving means operative.
4. In a telephone exchange system the combination with telephone lines, an automatic selector having trunk terminals arranged in groups, primary and secondary driving means for said selector, a sender adapted to control said primary driving means to set said selector in operative relation to one of said groups, means for rendering said secondary driving means automatically operative immediately upon the termination of said primary movement, of a relay (a) for each trunk operated when the same is seized, a circuit closed upon the 15 termination of said primary movement if all of the relays (a) of a group are operated and including a relay (117) which operates to prevent the closure of such secondary driving means, and means actuated 20 when one of said relays (a) becomes deenergized when the corresponding trunk becomes idle for deenergizing said relay (117) to render said secondary driving means operative.
5. In a telephone exchange system, the combination with telephone lines, an automatic selector having trunk terminals arranged in groups, primary and secondary driving circuits for said selector, an auxiliary switch associated with said selector 40 and having commutator segments, one for each trunk group, a sender adapted to control said primary driving circuit to place said selector in operative relation to one of said groups, means for automatically rendering said secondary driving circuit operative upon the termination of the primary movement, a relay (a) for each trunk operated when such trunk is seized, means adapted when all the relays of a group are 45 operated to ground the commutator segment of such group, a relay (117) and a circuit adapted to operate the same upon the termination of the primary movement of said selector if the corresponding segment is grounded, said relay being adapted to open said secondary driving circuit and when any trunk of the group becomes idle to become deenergized and to close said secondary driving circuit. 50
6. In a telephone exchange system, the combination with automatic selective switches, means for preventing the automatic testing operation of one of said switches when all the trunks of a selected group are busy, a source of signaling current, means for notifying the calling subscriber of such busy condition automatically actuated by the busy condition of the group for connecting said source to the calling line, and means automatically actuated when one of the trunks becomes idle for causing the switch to seize the same and disconnect said source from the calling line. 55
- In witness whereof, I hereunto subscribe my name this 8th day of September, A. D. 1917. 60
- CHARLES L. GOODRUM. 65
